UNITED STATES PATENT OFFICE.

DAVID J. MUNCY, OF LOCKNEY, TEXAS, ASSIGNOR TO W. F. JONS, OF LOS ANGELES, CALIFORNIA.

PUMP.

1,088,238.

Specification of Letters Patent.

Patented Feb. 24, 1914.

Application filed January 23, 1913. Serial No. 743,812.

To all whom it may concern:

Be it known that I, DAVID J. MUNCY, a citizen of the United States, residing at Lockney, in the county of Floyd and State of Texas, have invented certain new and useful Improvements in Pumps; and I do hereby declare the following to be a full, clear, and exact description of the invention, such as will enable others skilled in the art to which it appertains to make and use the same.

This invention relates to pumps, and it more particularly relates to pump valve-operating mechanisms.

15 An object of the invention is to greatly increase the flow of water through the pump without increasing the length of the stroke or number of strokes of the plunger rod.

Another object of the invention is to 20 provide a simple and improved mechanism whereby the water may be simultaneously lifted by force and by suction through the pump cylinder.

Other objects and advantages may be 25 recited hereinafter and in the claims.

In the accompanying drawings, which supplement this specification, Figure 1 is a vertical sectional view through the pump cylinder and casing on the line 1—1 of Fig. 30 2; Fig. 2 is a horizontal sectional view on the line 2—2 of Fig. 1.

In these drawings in which similar reference characters correspond with similar parts, throughout the several views, the 35 pump cylinder 5 is seated within an ordinary well casing 6, and within the cylinder 5 is seated a frame 7 having convexed ends 8 which are fitted snugly within the cylinder, against the opposite sides of the inner 40 wall thereof. Screws 9, or other proper means may be employed for securing the frame within the cylinder. This frame may be of any suitable form or structure, but in the present instance, it comprises two 45 parallel bars 10 having their ends connected by means of the externally convexed end sections 11. Pivots or axles 12 are seated in and supported by the bars 10, and on these pivots is journaled a pair of similar 50 spur-gear wheels 13, having bosses 14 which contact with the bars 10, so as to hold the gear teeth in equal spaced relation to the bars 10.

A double rack 15, having gear teeth on 55 two opposite sides, is engaged with the ad-

jacent teeth of both gear wheels, and is adapted to be raised and lowered by said gear wheels when they are rotated. On the lower end of the rack and to member 15 is secured a piston 16, of ordinary construction, adapted to allow the upward passage of water or liquid therethrough and to prevent it from passing downward therethrough. A somewhat similar piston 17 is fitted in the cylinder above the wheels 13, 60 and is connected with the wheels by means of a pair of racks 18 which engage with the respective wheels 13 at points diametrically opposed to the points at which the rack 15 engages with said wheels. In order that 65 the racks 18 may be retained properly in mesh with the teeth of the gear wheels, and at the same time, to minimize the friction, I provide rollers 19 in contact with the plane surfaces of the racks 18, opposite to 70 the teeth thereof, and I also provide rollers 20 against the opposite surfaces which are connected by said teeth; said rollers 19 and 20 being journaled in suitable bearings on the frame 10. Rollers 21 are also mounted 75 on the frame 10, and bear against two opposite sides of the rack 15, so as to retain the same in proper position and engagement with the wheels 13. Any proper means, as 80 for instance a retainer ring 22 may be secured within the cylinder 5, for preventing disengagement of the racks and gear wheels, as obviously, when the piston 17 has moved 85 into contact with the ring 22, the racks 18 and gear wheels 13 are still in mesh, and the said gear wheels are prevented from further rotation by means of said ring and said racks, and therefore, the rack 15 which is also still in mesh with the wheels 13, is 90 prevented from disengagement with the 95 teeth of the wheels 13.

In operation, assuming that the upper piston 17 is connected with a plunger rod (not shown), either through the medium of the upward extension of the racks 18, or by other suitable means, the said piston 17 may be caused to slide up and down in the cylinder between the gear wheels and the ring 22, thereby rotating the wheels 13 and thus causing the rack 15 to rise as the racks 18 descend. Now, assuming that the operation of the casing containing the cylinder 5 is wholly or partially submerged, the water or other liquid which is between the pistons 16 and 17 will be forced upward through the 100 105 110

latter, as the piston 17 descends and the piston 16 ascends. Next, as the motion of the pistons is reversed, the space therebetween is greatly enlarged, thereby tending to cause a vacuum between the pistons, and the consequent suction draws water or other liquid upward through the valve 16 and fills the space between the pistons; and, at the same time, the water liquid which has previously been forced through the piston 17 is now raised higher. Now, assuming that a stroke of four inches is imparted to the piston 17, it will be seen that a stroke of four inches is also imparted to the piston 16 through the medium of the wheels 13, so that when the piston 17 is in its upper position the piston 16 is eight inches farther removed therefrom that when it is in its lower position; so that each four-inch down-stroke of the pump sucks in an eight-inch column of water or oil, while each four-inch up-stroke of the pump discharges said eight-inch column of water or other liquid through the upper valve.

It will be seen that I have provided a pump of this character which is simple in construction, and which is fully capable of attaining the foregoing objects, in a thoroughly practical and efficient manner.

I do not limit my invention to the exact details of construction, combination and arrangement of parts, as herewith illustrated and described, but my invention may only be limited by a reasonable interpretation of the claims, nor do I confine the manufacture of this pump to any certain material or size,

but reserve the right to use any suitable material, or in any desired sizes; and for any use to which the pump could be used.

I claim:

1. In a pump, a cylinder, pistons slidable therein, oppositely extending rack bars secured to said pistons, a frame secured in said cylinder, said frame comprising spaced parallel bars, pinions mounted between said parallel bars and meshing with said rack bars, and means for guiding said rack bars, said means comprising rollers secured to said frame and bearing against said rack bars.

2. In a pump, a cylinder, pistons slidable therein, oppositely extending rack bars secured to said pistons, a frame secured in said cylinder, said frame comprising spaced parallel bars, end sections connecting said bars, said sections secured to said cylinder, spaced axles connecting said bars, pinions mounted on said axles between said parallel bars and meshing with said rack bars, rollers mounted on said parallel bars and bearing against said rack bars for guiding the same and rollers mounted on said end sections and bearing against the rack bars adjacent said end sections.

In testimony whereof I have signed my name to this specification in the presence of two subscribing witnesses.

DAVID J. MUNCY.
